SAW GUARD

Herbert E. Tautz, Milwaukee, Wis., assignor to
Delta Manufacturing Company, Milwaukee,
Wis.

Application September 20, 1933, Serial No. 690,248

19 Claims. (Cl. 143—159)

This invention relates to a saw guide and guard for use particularly with circular saws and similar tools.

More specifically the invention relates to a guard of what is known as the splitter type comprising essentially an element which enters the saw cut shortly after the workpiece leaves the saw, and holds the kerf open against any tendency of the wood to close, thus preventing binding on the saw and possible injury or inaccurate sawing of the workpiece, and danger to the operator.

Still more specifically the invention relates to a combination saw guard consisting of at least two separate members, one being a splitter guard of the type above defined and the other being an enclosing guard of the basket type which protects the hands and clothing of the operator from coming in contact with the saw blade, said two guards being capable either of independent use or of being used simultaneously.

A further object is to provide means whereby the basket guard may rise and fall with respect to the saw table without interference with the splitter guard, this being accomplished by providing a slot in a portion of the basket guard, or otherwise suitably shaping said basket guard, so as to clear the splitter guard.

Other objects of the invention reside in providing a splitter guard which may be readily placed in position for use and just as readily placed in another position where it is out of use and out of the way, but, nevertheless, secured against loss and ready for immediate readjustment into working position.

A further object is to provide a splitter guard which is capable of a slight "floating" movement, transverse to the plane of the saw, so that it may adjust itself to slight irregularities of the kerf and of the workpiece and thus prevent any accidental binding in the said workpiece.

A further feature of the invention resides in providing splitter guards of various thicknesses corresponding to various saws or other tools, in use on the circular saw table.

A further object is to provide a splitter guard which when placed upon a supporting arm provided for such purpose instantly and automatically adjusts itself into proper position, thus saving much time, which would otherwise be consumed in adjusting a splitter guard into proper position.

Other objects and advantages of the invention will in part be particularly pointed out in the

following specification and will in part be self-evident from the same.

In the drawings accompanying the present specification,

Figure 1 is a perspective view showing the combination splitter and basket guards, together with a supporting arm for the same and a fragmentary portion of a circular saw and saw table, the splitter guard being shown in the position it assumes when in use and the basket guard being 10 in its inactive position. 5

Figure 2 is a fragmentary perspective view showing both the splitter guard and the basket guard in active position on the table of a circular saw, 15

Figure 3 is a similar fragmentary perspective view showing the splitter guard in service alone,

Figure 4 is a corresponding fragmentary perspective view showing the basket guard being used alone, 20

Figure 5 is a fragmentary perspective view showing both guards swung to positions below the table top, thus freeing the saw for operations of types wherein the guards would interfere,

Figure 6 is a side elevation of the splitter 25 guard blade, and

Figure 7 is a fragmentary side elevation of a modified form of splitter guard blade.

Referring first to Figures 1 and 2, 1 designates the top of a saw table having therein the customary opening for receiving the saw 3 or other rotary tool, said opening being partially closed by a removable insert piece 2. This table may be supported by a suitable frame 4 in which is mounted the arbor or shaft 7 upon which the 35 saw or other tool 3 is mounted, said shaft being provided with a pulley 5 over which passes a suitable drive belt 6. 30

To the frame 4 may be secured a bracket or arm 15, as by screws 16 or the like. At its outer 40 end the bracket arm 15 may be provided with a suitable bore 17 adapted to receive one arm 12 (Fig. 5) of a substantially U-shaped guard support 8. This arm 12 may be turned freely in the bore 17 to adjust the U-shaped member 45 8 into any desired position and said member may then be secured in its adjusted position by tightening the clamping screw 13 by means of its handle 14. The U-shaped member 8 comprises also the relatively straight spacing portion 18 50 at right angles to the portion 12 and the further portion 11 which is bent back so as to extend parallel to the portion 12. The member 8 thus comprises the two supports 11 and 12 and the spacing means 18. It will be seen that by this 55

construction the U-shaped member 8 may be swung in the bore 17 about the axis of its arm 12, to bring the arm 11 either above the table, as shown in Figs. 1, 2, 3, and 4, or into a position 5 below the table, as shown in Fig. 5. The arm 12 is also slidable axially in the bore 17 to permit lateral relative adjustment thereof, as desired, and in fact the same may be entirely removed by sliding it completely out of said bore 17, when- 10 ever it is desired to do so.

The saw table may have the usual guide slots 9 therein for auxiliary appliances, which form no part of the present invention, such as miter gages or other sliding devices, and may be provided with the ripping fence 10 with apertures 15 23 therein, which is slidable over the top surface of the table 1 and securable by means of a nut 20 coacting with means 19, engaging the channel bar 22, fastened at the rear of the table by screws 20 21, as best shown in Fig. 5 and as claimed in the copending application, Serial No. 655,279.

The upper arm or support 11 of the U-shaped member 8 serves to provide a rod or pivot about which may be swung the member 30, which is pivoted about said arm 11, as shown, and to which are secured the two arms 24, as by screws 25. The member 30 may be retained against shifting axially on the arm 11 by means of two collars 32 and 33, placed beyond the respective 30 ends thereof, and retained adjustably in position by set screws 34 and 35, respectively. At their outer ends the arms 24 accommodate a pivot-shaft or pin 26, secured at each end by a suitable cotter pin or the like 27, preventing the arms 24 from spreading outwardly. About this shaft 26 is pivoted a saw guard 28 commonly known as of the "basket" type and having a sloping forward surface 31 adapted to be engaged and raised by a workpiece 136 when being fed to the saw, this being most clearly illustrated in Fig. 4.

This basket guard, when in the position shown in Fig. 4, completely protects the saw blade against accidental contact with the clothing or 45 person of the operator, automatically rising when the workpiece 136 is fed to the saw, by reason of the said sloping surface 31, and again falling back into place against the top of the saw table 1 when the workpiece 136 has passed 50 beyond the rear end of the guard. This guard may be swung into several positions, as shown for example in Figs. 1, 2, 4, and 5, being in its inactive position in Figs. 1 and 5 and in its active position in Figs. 2 and 4. As clearly shown in 55 Figs. 2 and 4 a slot 29 may be provided in the rear upper surface of the guard 28 for a purpose which will be explained hereinafter.

Referring now to Figs. 1 and 3, a guard of a different type is shown in position for use, namely, the splitter guard which is designated generally by reference character 40. This splitter guard consists primarily of a plate or blade of flat material, shaped as shown in Figs. 1, 2, 3 and 5, and as shown in detail in Fig. 6.

In Fig. 1 this guard is shown in place behind the saw blade 3 and substantially in the same plane as said saw blade so that a workpiece upon being ripped by the saw will pass partly on each side of the plate 40, with said plate engaging 65 in the saw kerf. The forward edge portion of the plate 40 is preferably bevelled, as shown at 48, the bevelled surface being formed as a curve corresponding to the size of the saw blade 3 so that when the saw blade 3 is advanced to its 70 greatest extent above the top 1 of the table, the

said bevelled edge will still clear the teeth of the saw by a sufficient margin of safety. The forward upper tip of the blade 40 is preferably rounded, as shown at 50, although the exact shape of said portion is not important.

The plate 40 preferably has a flat lower edge as indicated at 41, which can rest firmly against the top of the table 1, and in the rear of the said portion 41 a notch 48 may be provided, thereby keeping the top of said notched portion out of contact with the table so that any irregularities of the rear edge of said table will not affect the proper alignment and seating of the blade 40 upon the said table top. For a similar reason the downwardly depending portion 41 of the 15 blade is so shaped that it remains out of contact with the table 1 or the channel member 22 disposed at the rear thereof. Said depending portion 41 may be provided with an aperture 42, best shown in Fig. 6, which may be engaged over the 20 lower arm or support 12 of the U-shaped member 8. It may be secured upon said arm or rod 12 between two collars 52 and 53, as shown in Fig. 5, said collars being secured to the rod or arm 12 preferably by a set screw 54 and a thumb 25 screw 55, respectively, for simplicity of manipulation. A further collar 57 may be provided on the rod or arm 12 and secured thereto by a set screw 56, said collar 57 preventing the arm or support 12 from passing axially outward from 30 the position shown in Fig. 5, for example, and thus assuring the proper positioning of the U-shaped member 8 and the guards carried thereby with respect to the saw blade 3. The rear edge 46 of the plate or blade 40 may be of any desired 35 shape which does not interfere with the operation of the device, and is here shown as a circular arc, although it will be understood that this configuration is chosen merely for simplicity and good appearance, and many other shapes will be 40 equally satisfactory. A notched portion 44, here shown as semi-circular in shape, (see Fig. 6), may be provided at the rear upper end of the plate 40 and defined between the forward, somewhat blunt, point 45 and the rear elongated projection or tongue 43. A depression or recess 51 is provided below the tongue 43 for a purpose which will now be set forth.

Referring to Fig. 1, it will be seen that the elongated curved tongue 43 enters between the 50 rod 11 and the member 30 when the said member 30 is swung into the position shown in said Fig. 1, or when in the position shown in Fig. 5. The provision of the depression 51 thus makes it possible to swing the basket guard 28 into the inactive 55 position shown in Fig. 1 by providing room for the swinging of the member 30. It will be noted that the spacing between the aperture 42 and the notch 44 corresponds to the spacing of the supports or arms 11 and 12, so that the aperture 60 and notch may simultaneously engage said two supports. In Figs. 2 and 4 there is shown a slot 29 in the guard 28, Fig. 2 showing how said slot 29 cooperates with the blade 40 to allow the guard 28 to fall into position over the saw blade 65 3 in spite of the presence of the blade 40.

It will be noted from Fig. 3 that, if desired, the upper rearward end of the plate 40 may be supported on the support or rod 11 by means of the two collars 36 and 37 located upon said rod on 70 opposite sides of the notch portion 44 of the plate 40, said collars 36 and 37 being secured in their adjusted positions by means of the set screws 38 and 39, respectively.

Referring now to Fig. 7 it will be noted that 75

the blade 40 of Fig. 6 may be modified slightly by substituting a notch 58 for the aperture 42, said plate 40, in other respects, remaining identical with that shown in Fig. 6.

5 The operation of the device will be obvious from the preceding description thereof, but may be briefly summarized as follows:

If it be desired to employ the splitter guard alone, the machine may be set up as shown in Fig. 1 or in Fig. 3, Fig. 1 showing the basket guard 28 merely thrown backward into inactive position where it does not interfere with the splitter guard blade 40 and Fig. 3 showing the basket guard removed entirely, together with its supporting means 30, 24, etc. Usually it will be preferable to employ the Fig. 1 set-up, because such set-up does not necessitate removing the basket guard and yet brings it out of the way of the operator so that the splitter guard 40 alone may be used.

Theoretically a series of splitter guards 40 may be provided, varying in thickness to agree with the width of the saw kerf, or the thickness of the saw itself, measured across the "set" of the teeth, and in certain cases this may be desirable. However, in most cases a splitter guard of a single thickness may cooperate with saws of slightly different thicknesses, thus economizing in the expense and providing greater simplicity.

30 If, however, it is desired at any time to employ splitter guards of varying thicknesses, adjustment for this purpose is readily provided by means of the adjustable and removable collars 36, 37, 52 and 53, whereby it is evident that the blade 40 may be accommodated regardless of its thickness and may be adjusted into any desired position along the supports 11 and 12. It will be noted that the splitter guard blade 40 has preferably a bevelled forward edge 49, which readily enters into the saw kerf in spite of slight inaccuracies of alinement between blade 40 and saw 3.

45 It is also clear that the blade 40 need not be tightly clamped between the collars mentioned, but may be allowed a certain slight play so as to "float" and accommodate itself readily to inaccuracies of alinement or inaccuracies in the saw kerf, thus preventing a tendency to bind, which might otherwise occur if the splitter guard were held rigidly instead of being allowed to "float".

50 The splitter guard may be readily placed in position for service by removing the outer collar 53 by means of the conveniently located thumb screw 55, thus giving free access to the end of the rod 12, the said blade 40 being then engaged first with its notch 44 upon the rod 11 and then with its aperture 42 upon the rod 12, whereupon the collar 53 is replaced and secured by means of the thumb screw 55. Inasmuch as the spacing between the arms or rods 11 and 12 is substantially the same as the spacing between the aperture 42 and the notch 44 it is clear that this operation will lock the plate 40 securely upon the said two supports 11 and 12 and prevent any disengagement or loss thereof.

55 The same effect will be secured if the Fig. 7 type of blade is employed, because the notch 58 will serve equally as well as the aperture 42 to retain the corresponding portion of the blade securely locked in place. The Fig. 7 form of blade is, therefore, equivalent to the Fig. 6 form in most respects, but lacks the advantage that the Fig. 6 form may be permanently secured against loss on the rod 12 by merely slipping the aperture 42 over said rod and then securing the

plate by means of the collar 53 and thumb screw 55, allowing the blade to hang down freely from the rod 12 when not in use, that is, without the notch 44 simultaneously engaged upon the rod 11. By so doing the blade 40 may be protected against loss or damage, while not interfering in any way with the operation of the saw.

5 If it be desired to employ the splitter guard in combination with the basket guard the parts may be arranged as shown in Fig. 2, whereupon the slot 29 in the basket guard will permit said basket guard 28 to move up and down with respect to the saw table, without in any way interfering with the operation of the splitter guard. The splitter guard may in this case be 10 supported upon the rod 11 without employing the collars 36 and 37, if preferred, and to a certain extent it is immaterial whether or not such collars 36 and 37 are employed.

15 Fig. 4 shows how the basket guard 28 may be 20 used alone, the splitter guard 40 being either removed entirely from the machine or else swung into inactive position below the machine, as previously described.

25 Fig. 5 shows how it is possible to leave both 25 the basket guard 28 and the splitter guard 40 permanently attached to the machine, and ready for use again instantly when desired, but yet swung entirely out of the way below the table top so as not to interfere in any way with certain 30 operations of the saw, such as grooving or dado work, for example, where obviously a splitter guard cannot be used.

35 It is thus clear that there has been provided by the present invention a combination guard 35 comprising a splitter type guard and a basket type guard, which, however, are not rigidly secured to one another, but which are entirely independent of one another and which may be used either together or independently of one another and may even be swung in positions where they both are entirely out of the way when it is desired to dispense with their use, and that the splitter guard provided by the present invention may be secured either relatively rigidly or in a 45 floating manner, as desired, and may be held either only at its lower end or at both the top and bottom of the same, so as to adapt it to a vast variety of different conditions.

40 While a definite embodiment of such guards 50 has been illustrated and described in detail in the present drawing and specifications, it is, of course, clear that many changes and modifications can be made in various features thereof without departing from the spirit of the invention. 55

Therefore, the scope of the invention is to be determined by the following claims and is not to be held to be limited to the exact forms illustrated and described herein.

60 Having described my invention, what I claim is:—

1. A splitter guard for a circular saw having a frame, said guard comprising a flat plate having an aperture, a support fitting in said aperture 65 and secured to the frame of the saw, a second support, and means spacing said supports at a predetermined distance from one another, said plate having an open notch engageable upon said second support whereby the plate is retained in 70 a definite position with respect to said two supports and with respect to the saw.

2. A splitter guard for a circular saw having a frame, said guard comprising a flat plate having an aperture, a support fitting in said aper- 75

- ture and secured to the frame of the saw, a second support, and means spacing said supports at a predetermined distance from one another, said plate having an open notch engageable upon said second support whereby the plate is retained in a definite position with respect to said two supports and substantially in the plane of the saw.
3. A splitter guard for a circular saw having a frame, said guard comprising a flat plate having an aperture, and a U-shaped support having one of its arms fitting in said aperture and secured to the frame of the saw, said plate having an open notch engageable upon the other arm of said support whereby the plate is retained in a definite position with respect to said two arms and substantially in the plane of the saw.
4. A splitter guard for a circular saw having a frame, said guard comprising a flat plate having an aperture, a support fitting in said aperture and secured to the frame of the saw, means preventing excessive transverse movement of said plate with respect to the support, a second support, and means spacing said supports at a predetermined distance from one another, said plate having an open notch engageable upon said second support whereby the plate is retained in a definite position with respect to said two supports and substantially in the plane of the saw.
5. A splitter guard for a circular saw having a frame, said guard comprising a flat plate having an aperture, a U-shaped support having one of its arms fitting in said aperture and secured to the frame of the saw, and means for removably securing said plate to said arm, said plate having an open notch engageable upon the other arm of said support whereby the plate is retained in a definite position with respect to said two arms and substantially in the plane of the saw.
6. A splitter guard for a circular saw having a frame and a support secured to said frame, said guard comprising a flat plate having a portion of its periphery shaped to engage said support, means cooperating with said support to retain the plate against excessive transverse movement, a second support, and means spacing said supports at a predetermined distance from one another, said plate having another portion of its periphery engageable upon said second support, whereby said plate is retained in a definite position with respect to said two supports.
7. A splitter guard for a circular saw having a frame, and a U-shaped support, means securing said support to the frame, said guard comprising a flat plate, said plate being shaped to engage one arm of said support, and means for removably securing said plate to said arm, said plate also having an open notch engageable upon the other arm of said support whereby the plate is retained in a definite position with respect to said two arms and substantially in the plane of the saw.
8. A splitter guard for a circular saw having a frame and a support secured to said frame, said guard comprising a flat plate having a portion of its periphery notched to engage said support, means cooperating with said support to retain the plate against excessive transverse movement, a second support, and means spacing said supports at a predetermined distance from one another, said plate having another portion of its periphery notched to engage said second support, whereby said plate is retained in a definite position with respect to said two supports.
9. A splitter guard for a circular saw having a frame, and a U-shaped support, means securing said support to the frame, said guard comprising a flat plate, said plate being peripherally notched to engage one arm of said support, and means for removably securing said plate to said arm, said plate also having an open notch engageable upon the other arm of said support whereby the plate is retained in a definite position with respect to said two arms and substantially in the plane of the saw.
10. A combination guard for a circular saw having a frame and a support secured to said frame, said combination guard comprising a basket guard pivoted to said support and a splitter guard secured to said support, said basket guard being shaped to receive and move freely past the splitter guard in such solely pivotal movement.
11. A combination guard for a circular saw having a frame, said combination guard comprising a basket guard pivotally secured to said frame and a splitter guard also secured to said frame, said basket guard being shaped to receive and move freely past the splitter guard in such solely pivotal movement.
12. A combination guard for a circular saw having a frame, said combination guard comprising a basket guard pivoted to the said frame and a splitter guard secured to said frame, said basket guard having a portion thereof cut away, said splitter guard being located within said cut-away portion, whereby the basket guard may move freely past said splitter guard in such solely pivotal movement.
13. A combination guard for a circular saw having a frame and a support secured to said frame, said combination guard comprising a basket guard pivoted to said support and a splitter guard secured to said support, said basket guard having a portion thereof cut away, and said splitter guard being located within said cut-away portion, whereby the basket guard may move freely past said splitter guard in such solely pivotal movement.
14. A combination guard for a circular saw having a frame and a support secured to said frame, said combination guard comprising a basket guard pivoted to said support and a splitter guard secured to said support, said basket guard having a slot therein, and said splitter guard being located within the confines of said slot, whereby the basket guard may move freely past said splitter guard in such solely pivotal movement.
15. A splitter guard for a circular saw having a frame and a support secured to said frame at a definite distance from the axis of the saw blade, said guard comprising a flat plate having an aperture therein, said support being engaged in said aperture, thus permitting solely pivotal movement of said plate about said support, whereby the plate may be pivoted into or out of its active position with respect to the blade of the circular saw, without striking said saw blade.
16. A splitter guard for a circular saw having a frame, said guard comprising a flat plate having an aperture, a U-shaped member, means for pivotally securing one arm of said U-shaped member to said frame, said arm passing through the aperture of the plate, said plate having a notch upon its periphery and in engagement with the other arm of the U-shaped member, whereby said plate may be swung into and out of active position with respect to the blade of

the saw by turning said U-shaped member in its pivotal support.

17. A combination guard for a circular saw having a frame, said combination guard comprising a guard pivotally secured to the frame, a splitter guard secured to the frame, said first-named guard straddling the splitter guard, and means whereby the first-named guard may be swung into and out of active position with respect to the blade of the saw and past the splitter guard without interfering with the said splitter guard.

18. A splitter guard for a circular saw having a frame, said guard comprising a flat plate having an aperture therein and a support secured to the frame at a definite distance from the axis of the saw blade and passing through said aperture whereby said plate may pivot about the support into and out of active position with respect to the

blade of the saw, without striking said saw blade, by such solely pivotal movement, and further means cooperating with the support to retain the blade in its desired position axially of the support.

19. A splitter guard for a circular saw having a frame, and a support secured to said frame, said guard comprising a flat plate having an aperture therein, said support passing through said aperture and serving as a pivot for the plate, an abutment, means for adjustably securing said abutment to said support, a retaining member removably secured to said support on the opposite side of said plate, the plate being retained between said abutment and said member, whereby the plate may be readily removed from and replaced on the support without disturbing its desired alinement with the blade of the saw.

HERBERT E. TAUTZ.
